UNITED STATES PATENT OFFICE.

SIGMUND SCHIFF, OF NEW YORK, N. Y.

NECK-ROLL APPARATUS FOR BOTTLE-MAKING.

1,130,845.

Specification of Letters Patent. Patented Mar. 9, 1915.

Application filed January 14, 1914. Serial No. 811,942.

To all whom it may concern:

Be it known that I, SIGMUND SCHIFF, a subject of the King of Hungary, residing in New York city, county and State of New York, have invented certain new and useful Improvements in Neck-Roll Apparatus for Bottle-Making, of which the following is a specification.

My invention is a neck roll apparatus for forming and finishing bottle-neck heads and especially their bores. It is especially designed for use in bottle machines; whose output will be considerably increased in number and cheapened by its use.

15 The particular apparatus illustrated is designed to form and finish bottle neck heads for the use of the capillary valve disclosed in my co-pending application, Serial No. 749086, and to be used in bottle machines 20 which make bottles in molds, from tank glass.

In the accompanying drawings all the sections are axial except Figures 6 and 7.

Fig. 1 is a general section, Fig. 2 an enlarged section of the principal revolving members, Fig. 3 a section of the roller, the thimble, and its charge of glass prior to rolling, and Fig. 4 a section of the rolled and finished neck head. The remaining figures illustrate the eccentric displacement of the roller and means to accomplish the same, Fig. 5 being a diagram, Fig. 6 a plan (with the driving shaft in section) showing the eccentric as locating the roller axially, and Fig. 7 a corresponding view when its eccentricity is maximum. The plunger is shown in the same position in Figs. 3, 4, 6 and 7.

My apparatus can be adapted to any method of, or machine for, making bottles, 40 as for instance, United States Patent No. 766,768, issued to M. J. Owens, August 2, 1904. The drawings illustrate only one arm *a* of the revolving head frame,—the adapter *b*,—(which is the member precisely operably 45 locating my roll) and the neck mold *c*,—of a machine of known type which gathers the viscous glass from a revolving tank, by vacuum, into blank molds (not shown) and thimbles *d*, cuts off the glass with a knife, 50 forms the neck-heads, substituting finishing molds for the blank molds, and blows, finishes and delivers the bottles. Such a bottle machine has parts not necessary to illustrate, but whose functions should be understood, such as means to cause vacuum and

supply compressed air, and machine members to manipulate the head frame and, with it, the charged molds and the bottles, during their manufacture. Further reference to the bottle machine is unnecessary except to state 60 that the motive shaft *M* of my apparatus is suitably geared to and intermittently driven from transmission members thereof (by toothed gearing) and that I substitute a specially designed plunger *1*, having a revolving head or mushroom, *1^a*, for the plunger now in use, like which it is periodically lifted out of the way of and replaced by the blower slide; no change in the other usual bottle machine design being necessary. 70

It must be understood that the adapter *b*, the neck mold *c* and the thimble *d* must be special to the particular kind and finish of bottle to be made; and that suction passages *e* are formed in the adapter *b*, arm *a* and neck-mold *c*, through which the blank mold and the bore of the thimble *d* may communicate with the vacuum apparatus of the bottle machine, for the purpose of gathering glass. 80

I mount my apparatus coaxial with the bottle, the thimble *d* and the adapter *b*, on the plunger-reciprocating members of the bottle machine by means of a tubular stock 2 provided with medial and outer bearings 85 20 and 21 for the primary shaft 10; and a bearing formed in an arm 22, for the motive shaft *M*, which is rendered flexible by a universal joint *m*. Bevel gears, 11, connect the motive and primary shafts, *M* and 10; 90 and on the inward end of the latter I fix a clutch member, preferably a disk 12 in whose face are radial, parallel-sided grooves 13.

Revolute on and detachable from the inward end of the stock 2 is a head or mushroom 1^a formed with an annular bearing face 1^b which makes air-tight joint with the face of the adapter *b* exterior to the suction passages *e* therein and to a suction recess 1^c communicating therewith; and a tubular 95 stem, 1^d revolute in a bearing axial in the adapter, having in its face axially extending suction channels 1^e which connect said recess 1^c with the thimble *d* and the mold, and containing an eccentric bearing 1^f. The 100 forming and finishing roll 4 is made with conformations corresponding with those to be rolled into the bottle neck; in this case with grooves 40 which form contracted rings 41 and their capillary surfaces and 41 110

which forms a valve seat. When idle it is axial in the thimble bore, when revolved it is eccentrically displaced therein, and it is mounted and driven as follows: As diagrammed in Fig. 5, the center F of the bearing 1' in the mushroom 1^a is eccentric to the axis A of the bottle, which is the general work-axis of the apparatus. In the bearing 1' is an eccentric 5 and thereon, eccentric thereto by an eccentricity equal to that of the bore 1' of the mushroom 1^a, a tubular driving shaft 5—and a hollow roll shaft 51, which is stepped to secure maximum strength, terminates in a teat 52 and is axially tapped for a screw 53 which holds the roll 4 on the shaft 51. As hereinafter explained, I have found in actual manufacture that the roll 4 must be operative somewhat within the bottle necks in order to make them perfect; and I therefore space the roll 4 from the mushroom stem 1^a by a hollow former, 1^b, driven into a socket in said stem co-axial with the bottle, the bottle mold and the adapter, and whose bore gives clearance for the roll shaft 51.

The driving shaft 50 terminates in a dog 54 provided with an interrupted, parallel-sided tooth 55 which engages one of the grooves 13 in the clutch head 12 of the driving shaft 10, to drive the apparatus by contact surfaces ample to secure durability and whose axis is perpendicular to the axis of eccentricity X of the eccentric 5, so that when it shifts the roll 4 said tooth can slide in said groove to render the engagement flexible with respect to said motion while otherwise unyielding.

I provide between the stock 2 and the revolving parts (the mushrooms, eccentric and roller) a connection which permits them to be readily removed and reassembled and which comprises, loose on the driving shaft 50 and adjacent to its terminal disk 54, a collar, 56, having in its face a groove 57; and on the stock 2 a socket 23 and mounted therein a manually retractable pin 24, normally advanced by a spring 25 and engaged with the groove 57.

Adjacent to the collar 56 I pin to the shaft 50 a disk 58 having a shift arm 5^a for shifting the eccentric 5 and displacing the roll 4 and between the disk 58 and the adjacent face of the mushroom 1^a I interpose a roller or ball thrust bearing 60; and in some cases I may interpose a like bearing between the end of the stock 2 and the disk 58. On the mushroom 1^a, I form a tubular stump 1^b in which the end of the stock 2 makes a loose fit to complete the housing of the running parts, which contains the disk 58 and roller bearing 60 and whose wall is slotted to form two stops 1^l and 1^k which limit the motion of the shift arm 5^a and the displacement of the roller 4.

To graduate the rolling and automatically

return the eccentric 5 and roll 4 to their neutral, normal position after rolling is completed, so that the roll can be withdrawn from the finished bottle neck, I connect the eccentric 5 and mushroom 1^a by a spring 59 illustrated as coiled spring hooked at one end to the arm 5^a and having a graduating connection with the mushroom illustrated as a tang on the spring and a properly-spaced series of holes, 1^m, in the mushroom, into one or other of which the tang of the spring 59 is hooked.

The operation of my roll is greatly improved by properly adjusting the effort of the spring 59 to the frictional resistance to 80 rotation of the mushroom 1^a and the resistance of the viscous glass in the thimble d to the displacement of the roll. The latter is a natural variable, increasing with the cooling of the glass; and the former is generally a variable, in bottle machines, because the bottle machine members which reciprocate the plunger 1 are generally spring-cushioned and so designed, actuated and controllable that the plunger is 90 brought without shock into contact with the adapter and subsequently pressed against it with a graduated pressure, which is readily controllable. Further, in machines which gather glass by suction, for which my apparatus is especially designed, just before and during the initiation of rolling, the mushroom 1^a is pressed against the adapter by more or less unbalanced atmospheric pressure, due to the high vacuum between them, 100 which is readily controllable by parts essential to the operation of the bottle machine.

In order that the effort of the spring 59 may be adjusted with precision to the above described unavoidable resistances, all other resistances should be, as nearly as possible, eliminated, and to that end I introduce the ball bearing or bearings 60.

If the spring 59 be weak relatively to the resistances, it does not graduate the eccentric displacement of the roll, but merely returns it to coaxiality after rolling is completed: When power is applied the transmission instantly swings the eccentric arm 5^a from the rest stop 1^l to the driving stop 1^k. 110 115 120 125 130 displaces the roll secantwise and initiates maximum rolling; and at the end of the cycle, when the power is suspended, the spring returns the eccentric and roll to coaxiality. This mode of operation is suitable for some kinds of bottles. But if the spring 59 be nicely adjusted relatively to the resistance, when power is applied the arm 5^a gradually strains the spring, the spring initiates and accelerates the rotation of the mushroom and the roll 4 is displaced in a spiral until the arm 5^a contacts with the driving shoulder 1^k after which the eccentric and mushroom revolve as one piece with the roll 4 at its maximum eccentricity; and

at the end of the cycle, when power is suspended, the spring returns the roll to coaxiality. Care must be taken to adjust the spring so that the arm 5^a will, without risk 5 of failure, contact with the driving stop 1^k and the roll 4 will be fully displaced, because otherwise the bottle neck bores would be too small and the roll might not be removable therefrom.

10 To cool the roll 4, I provide a cooling system comprising an aperture in the wall of the stock 2 connecting its bore with an air supply system of the bottle machine; suitable air channels 27, where necessary, for the flow of air from the stock bore into the bores of the driving shaft 50; a reducing tube 5^c connecting the bore of the eccentric 5 with the extremity of the bore in the roller shaft 51 and forming therein an annular cooling 15 chamber 5^e which discharges into free air through a passage 5^d bored in the eccentric.

20 My apparatus operates thusly: The assembled mushroom 1^a, eccentric 5 and roll 4 can be removed from the stock 2 (when the latter is lifted) after pulling out the spring-pin 24. The eccentric and its belongings can be separated from the mushroom after removing the screw 53 and roll 4. The speed at which the roll 4 is eccentrically displaced 25 and rolling initiated can be graduated by adjusting the tang of the regulating spring 59 into the suitable hole 1^m in the mushroom. Normally the spring 59 positions the shift arm 5^a of the eccentric against the rest stop 30 1^l (Fig. 6) and the eccentric 5 so that the shafts 50 and 51 and roller 4 are coaxial with the bottle machine and bottle molds, that is to say, on the line F—A—X, Fig. 5. While so positioned the glass is gathered, 35 and immediately thereafter the motive shaft M begins to be revolved (by the aforesaid connection) and to drive the apparatus. The plunger 1 being pressed upon the adapter b by the operation of bottle-machine parts (not illustrated) its friction 40 holds it back and causes the primary and driving shafts 10 and 50 to begin to turn the eccentric 5 in the eccentric bearing 1^t of the mushroom 1^a, strain the spring 59, and there- 45 by graduate the shifting of the eccentric, the displacement of the roll 4 and the initiation of rolling. After the eccentric arm 5^a has been fully shifted to contact with the driver stop 1^k, the eccentric 5, mushroom 50 and former 1^g revolve as one piece, and the roll 4 revolves with them and the rolling effect is maximum, the axis of eccentricity X and axis of the shafts 50 and 51 and roller 4 having been shifted from the line F—A—X 55 (Fig. 5) to that F—E—X and the shaft-and-roller axis from A to E.

60 The freshly gathered glass usually completely fills the annular space between the rollers 4 and 1^g and the wall of the thimble d (save for the air which adheres thereto

and accidental small air bubbles) as shown in Fig. 3. As rolling is initiated the roll 4 is shifted across the extremity of the former 1^g, to its final position (Figs. 4, 5 and 7). The glass is rolled into all cavities 70 and bubble-holes and perfectly fills out the neck-head, even if the thimble be not perfectly charged, such air as there may be is driven into the space in which the roll works, and, expanding therein, downwardly 75 enlarges said space (Fig. 4) which is due mainly to the sagging of the glass charge when the knife retires from under the blank mold: the surplus glass is extruded into the blank mold; and the neck head is 80 rolled, finished and sufficiently cooled and hardened, solid and perfect.

85 The above described operations are done in a fraction of a second. In bottle machines of the type referred to, they are done during the small angular movement of the arm a beginning substantially at the completion of glass-gathering and terminating substantially as the knife completes its function and the plunger begins to lift out of 90 the way of the blower slide. After the bottle necks or it may be, neck heads are rolled as aforesaid, the bottles are blown in the usual manner.

95 In practical manufacture, I find that glass cools and hardens so rapidly in the nozzle and its extremity that a roll which (like my roll 4) does any considerable amount of work, must be located a considerable distance within the neck head where the glass 100 keeps its heat better, as in the illustrations, and that attempts to extend the roll to and roll the extremity and tip of the nozzle fail because the quickly setting glass adheres to the top of the roll, and not only are the nozzles spoiled but also the rolls, whereas a former like that 1^g, rotated on the bottle axis, and doing no more rolling than is due to the tremor of the apparatus, operates satisfactorily and, in connection with the 105 roll 4, reliably produces a perfect bottle, provided that the surface of the former 1^g be made a truncated cone merging into a fillet, 1^h, which, during the work, merges substantially into the head-conformation of 110 the thimble d. I find that a truly cylindrical surface in the former 1^g of a flat annulus thereon extending over the end of the bottle nozzle, tears the glass and spoils the work. 115

120 Having thus described my invention, I claim:—

1. Neck-roll apparatus for conforming bottle necks, adapted to operate in connection with bottle molds and comprising a 125 mounting member adapted to mount a roll operably relatively to a bottle mold, a roll adapted to be located, revolved and eccentrically displaced in a bottle mold, displacing means adapted to displace said roll and 130

its axis from a concentric position in said bottle mold, and driving mechanism adapted to revolve said roll.

2. Neck-roll apparatus for conforming 5 bottle necks, adapted to operate in connection with bottle molds and comprising a mounting member adapted to mount a roll operably relatively to a bottle mold, a former adapted to mold the outward nozzle 10 of a bottle neck, a roll adapted to be located adjacent to said former, and revolved and eccentrically displaced in a bottle mold, displacing means adapted to displace said roll and its axis from a concentric position 15 in said bottle mold, and driving mechanism adapted to revolve said roll.
3. Neck-roll apparatus for conforming 20 bottle necks, adapted to operate in connection with bottle molds and comprising a mounting member adapted to mount a roll operably relatively to a bottle mold, a roll adapted to be located, revolved and eccentrically displaced in a bottle mold, conformations on said roll corresponding with 25 formations to be formed in bottle necks, displacing means adapted to displace said roll and its axis from a concentric position in said bottle mold, and driving mechanism adapted to revolve said roll.
4. Neck-roll apparatus for conforming 30 bottle necks, adapted to operate in connection with bottle molds and comprising a mounting member adapted to mount a roll operably relatively to a bottle mold, a roll adapted to be located, revolved and eccentrically displaced in a bottle mold, displacing means adapted to displace said roll and its axis from a concentric position in 35 said bottle mold, graduating means adapted to graduate the eccentric displacement of said roll, and driving mechanism adapted to revolve said roll.
5. Neck-roll apparatus for conforming 40 bottle necks, adapted to operate in connection with bottle molds and comprising a mounting member adapted to mount a roll operably relatively to a bottle mold, a hollow roll adapted to be located, revolved and eccentrically displaced in a bottle mold, displacing means adapted to displace said roll and its axis, cooling means connected with the interior of and adapted to cool said roll, and driving mechanism adapted to revolve 45 said roll.
6. Bottle-neck-conforming roll apparatus 50 adapted to operate in connection with bottle neck molds and comprising a locating member connected with such mold and containing a bearing coaxial therewith; a bearing member revolvable in said bearing and containing a bearing eccentric thereto; angularly movable in said eccentric bearing, an eccentric; thereon a roll adapted to be revolved in, and by angular movement of 55 said eccentric, to be located coaxial with and eccentric to, such mold; connecting said eccentric and bearing member, an automatically-graduating connection adapted to graduate the rate of eccentric displacement of said roll; means to revolve said roll and displace it to eccentricity as aforesaid; and means to return it to coaxiality.
7. Bottle-neck-conforming roll apparatus 60 adapted to operate in connection with a bottle-neck mold and comprising a locating member connected with such mold and containing a bearing coaxial therewith; a bearing member revolvable in said bearing and containing a bearing eccentric thereto; operably connected with, and during each cycle, initially angularly movable in said eccentric bearing, and thereafter serving to drive said bearing member, an eccentric; 65 thereon a roll adapted to be revolved in, and by angular movement of said eccentric to be located coaxial with and eccentric to, such mold; means to revolve said roll and displace it to eccentricity as aforesaid; and 70 means to return it to coaxiality.
8. Bottle-neck-conforming roll apparatus 75 adapted to operate in connection with a bottle-neck mold and comprising a locating member connected with such mold and containing a bearing coaxial therewith; a bearing member revolvable in said bearing and containing a bearing eccentric thereto; angularly movable in said eccentric bearing, an eccentric; thereon a roll adapted to be revolved in, and by angular movement of 80 said eccentric, to be located coaxial with and eccentric to, such mold; connecting said eccentric and bearing member, an automatically-graduating connection adapted to graduate the rate of eccentric displacement of said roll; means to revolve said roll and displace it to eccentricity as aforesaid; and 85 means to return it to coaxiality.
9. Bottle-neck-conforming roll apparatus 90 adapted to operate in connection with a bottle-neck mold and comprising a locating member connected with such mold and containing a bearing coaxial therewith; a bearing member revolvable in said bearing and containing a bearing eccentric thereto; angularly movable in said eccentric bearing, an eccentric; thereon a roll adapted to be revolved in, and by angular movement of 95 said eccentric, to be located coaxial with and eccentric to, such mold; connecting said eccentric and bearing member, an automatically-graduating connection adapted to 100 graduate the rate of eccentric displacement of said roll; means to revolve said roll and displace it to eccentricity as aforesaid; and means to return it to coaxiality.
10. Bottle-neck-conforming roll apparatus 105 adapted to operate in connection with a bottle-neck mold and comprising a locating member connected with such mold and containing a bearing coaxial therewith; a bearing member revolvable in said bearing and containing a bearing eccentric thereto; angularly movable in said eccentric bearing, an eccentric; thereon a roll adapted to be revolved in, and by angular movement of 110 said eccentric, to be located coaxial with and eccentric to, such mold; connecting said eccentric and bearing member, an adjustable, automatically-graduating connection adapted to 115 graduate the rate of eccentric displacement of said roll; means to adjust said connection; means to revolve said roll and displace it to eccentricity as aforesaid; and means to return it to coaxiality.
11. Bottle-neck-conforming roll apparatus 120 adapted to operate in connection with a bottle-neck mold and comprising a locating member connected with such mold and containing a bearing coaxial therewith; a bearing member revolvable in said bearing and containing a bearing eccentric thereto; an- 125

- gularly movable in said eccentric bearing an eccentric; thereon a roll adapted to be revolved in, and, by angular movement of said eccentric, to be located coaxial with and 5 eccentric to, such mold; means to revolve said roll and displace it to eccentricity as aforesaid; and between said eccentric and bearing member a spring adapted at cycle-ends to return it to coaxiality.
- 10 11. Bottle-neck-conforming roll apparatus adapted to operate in connection with a bottle-neck mold and comprising a locating member connected with such mold and containing a bearing coaxial therewith; a bearing member revolvable in said bearing and containing a bearing eccentric thereto; angularly movable in said eccentric bearing an eccentric; thereon a roll adapted to be revolved in, and, by angular 15 movement of said eccentric, to be located coaxial with and eccentric to, such mold; means to revolve said roll and displace it to eccentricity as aforesaid; and between said eccentric and bearing member a 20 spring adapted to graduate the rate of eccentric displacement of said roll, and at cycle-ends, to return it to coaxiality.
12. Bottle-neck-conforming roll apparatus adapted to operate in connection with a bottle-neck mold and comprising a locating member connected with such mold and containing a bearing coaxial therewith; a bearing member revolvable in said bearing and containing a bearing eccentric thereto; operably connected with, and during each 25 cycle, initially angularly movable in, and thereafter serving to drive said eccentric bearing, an eccentric; thereon a roll adapted to be revolved in such bottle-neck mold and, by angular movement of said eccentric, to be located coaxial with and eccentric to such mold; means to revolve said roll and displace it to eccentricity as aforesaid; between said eccentric and bearing member a spring 30 adapted to graduate the rate of eccentric displacement of said roll, and at cycle-ends, to return it to coaxiality; and adjustment means to adjust the resistance of said spring.
13. Neck roll apparatus for conforming bottle necks, adapted to operate in connection with a bottle machine member and a bottle neck mold operably located on a work axis of such machine and comprising a bearing member revolvable in a bearing of said 35 machine member on said axis and containing a bearing eccentric thereto; angularly movable in said eccentric bearing, an eccentric; thereon a roll adapted to be revolved in such mold and, by angular motion of said eccentric relatively to said bearing member, to be located on and displaced from said axis; means to revolve said roll and displace it from said work-axis; and means to return it thereto.
14. Neck roll apparatus for conforming bottle necks, adapted to operate in connection with a bottle machine member and a bottle neck mold operably located on a work axis of such machine and comprising a bearing member revolvable in a bearing of said machine member in said axis and containing a bearing eccentric thereto; a bearing eccentric thereto; a tubular former axial on said bearing member and extending into said mold; angularly movable in said eccentric bearing, an eccentric; thereon and 40 shiftable across the extremity of said former, a roll adapted to be revolved in such mold and, by angular motion of said eccentric relatively to said bearing member, to be located on and displaced from said axis; means to revolve said roll and displace it from said work-axis; and means to return it thereto.
15. Neck roll apparatus for conforming bottle necks, adapted to operate in connection with a bottle machine member and a bottle neck mold operably located on a work axis of such machine and comprising a bearing member revolvable in a bearing of said machine member on said axis and containing a bearing eccentric thereto; axial on said bearing, extending into said mold, adapted to form the nozzles of bottle-heads, a tubular former having its conforming surface a truncated cone; angularly movable in said eccentric bearing, an eccentric; thereon a roll adapted to be revolved in such mold and, by angular motion of said eccentric relatively to said bearing member, to be located on and displaced from said axis; means to revolve said roll and displace it from said work axis and means to return it thereto.
16. Neck roll apparatus for conforming bottle necks, adapted to operate in connection with a bottle machine member and a bottle neck mold operably located on a work axis of such machine and comprising a bearing member revolvable in a bearing of said machine member on said axis and containing a bearing eccentric thereto; axial on said bearing, extending into said mold, adapted to form the nozzles of bottle-heads, a tubular former having its conforming surface a truncated cone merging into a fillet; angularly movable in said eccentric bearing, an eccentric; thereon a roll adapted to be revolved in such mold and, by angular motion of said eccentric relatively to said bearing member, to be located on and displaced from said axis; means to revolve said roll and displace it from said work-axis; and means to return it thereto.
17. Bottle-neck-conforming roll-apparatus adapted to operate in connection with an adapter of a bottle machine and air passages therein and with a bottle neck mold operably located on a work axis of such machine and adapter, and comprising a head revolvable in a bearing of said adapter on said axis, containing a bearing eccentric thereto.

- and formed with air passages adapted to connect said mold with said air passages of such machine; angularly movable in said eccentric bearing, an eccentric; thereon a roll 5 adapted to be revolved in such mold and by angular motion of said eccentric relatively to said head, to be located on and displaced from said axis; an operable connection between said eccentric and head adapted, during each 10 cycle to initially permit relatively angular motion of and thereafter compel synchronous revolution of said eccentric and head; and means to revolve said eccentric, roll and head.
- 15 18. Bottle-neck-conforming roll-apparatus adapted to operate in connection with an adapter of a bottle machine and air passages therein and with a bottle neck mold operably located on a work axis of such machine and 20 adapter, and comprising a tubular stock adapted to be operably connected with members of said bottle machine, a transmission shaft in said stock adapted to be operably connected with and intermittently driven 25 by members of said bottle machine; a head detachably connected with said stock revolvable in a bearing of said adapter, on said axis, containing a bearing eccentric thereto and formed with air passages adapted to 30 connect said mold with said air passages of such machine; angularly movable in said eccentric bearing, an eccentric; thereon a roll adapted to be revolved in such mold and by angular motion of said eccentric 35 relatively to said head, to be located on and displaced from said axis; an operable connection between said eccentric and head adapted, during each cycle, to initially permit relative angular motion of and thereafter 40 compel synchronous revolution of said eccentric and head; and an operable connection between said eccentric and said transmission shaft.
19. Bottle-neck-conforming roll-apparatus 45 adapted to operate in connection with an adapter of a bottle machine and air passages therein and with a bottle neck mold operably located on a work axis of such machine
- and adapter, and comprising a head revolvable in a bearing of said adapter, on said axis, containing a bearing eccentric thereto and formed with air passages adapted to connect said mold with said air passages of such machine; angularly movable in said eccentric bearing, an eccentric; thereon a roll 55 adapted to be revolved in such mold and by angular motion of said eccentric relatively to said head, to be located on and displaced from said axis; an operable connection between said eccentric and head adapted, during each cycle, to initially permit relative angular motion of and thereafter 60 compel synchronous revolution of said eccentric and head, a dog engagement between said eccentric and transmission shaft comprising a 65 dog and a dog-engaging member on the same respectively; and a pin and groove engagement between said eccentric and said stock.
20. Neck-roll apparatus for conforming 70 bottle necks, adapted to operate in connection with a bottle machine member and a bottle neck mold operably located on a work axis of such machine and comprising a bearing member revolvable in a bearing of said 75 machine member on said axis and containing a bearing eccentric thereto; angularly movable in said eccentric bearing, an eccentric, thereon a roll adapted to be revolved in such mold and, by angular motion of said eccentric relatively to said bearing member, to be located on and displaced from said axis; means to 80 revolve said roll and displace it from said work-axis and means to return it thereto, and an air circulating system comprising a 85 bore within said roll, a bore in said eccentric, connected therewith a pipe extending into and forming an annular air passage in said bore within the roll and connected with said passage a passage extending through said eccentric.
